BLACK-OUT SHADE

Benjamin Hendon, Brooklyn, N. Y.

Application August 11, 1942, Serial No. 454,367

1 Claim. (Cl. 340—108)

The present invention relates to new and useful improvements in lamp shades, and more particularly it pertains to a lamp shade especially adapted for use in shielding or masking sources of light during the so-called blackout periods.

It is the object of the present invention to provide a novel construction of lamp shade which will effectively mask or shield a source of light to an extent which will render the same invisible from without the compartment in which the light source is located, and yet provide sufficient illumination within said compartment, to render visible the general locations of its various furnishings and contents.

It is a further object of the invention, so to construct the device that it may be employed in connection with lighting fixtures of conventional construction and type.

Other objects of the invention will become apparent as the nature of the invention is better understood for which purpose, reference will now be had to the accompanying drawing and the following description thereof.

In the drawing,

Figure 1 is a perspective view of a lamp shade constructed in accordance with the present invention, illustrating one manner in which the shade may be employed,

Figure 2 is an enlarged central vertical sectional view of the shade illustrating the light source therein,

Figure 3 is a horizontal sectional view taken substantially on the line 3—3 of Figure 2, and;

Figure 4 is a central vertical sectional view on a reduced scale illustrating a slightly modified form of the invention.

Referring to the drawing by reference characters, the shade is designated B.

While the shade may be constructed in many shapes or forms, I prefer to make the body portion 10 thereof of cylindrical form as herein illustrated.

The body portion has a fixed end wall 11 and a removable end wall 12, the latter having an annular flange 13 which receives and frictionally engages the open end 14 of the body portion 10 to retain the removable end wall upon the open end of the body portion to close the same.

The body portion 10 and the fixed end wall 11 are provided with a suitable lining 15, and the removable end wall 12 has a similar lining 16.

These linings 15 and 16 are formed from any suitable fire resistant material which is also possessed of opaque qualities to render the shade both fire resistant and opaque when the body 55

portion and end walls are formed of such materials as do not have these qualities.

The fixed end wall 11 has a centrally disposed opening 20 for the reception of a combined plug and socket fixture 21 which latter is formed with means for retaining it in position in the opening 20.

In the present embodiment of the invention the plug and socket member 21 is provided with 10 two spaced beads 22 which form an intermediate channel 23 for the reception of the defining edge of the opening 20 of the housing end wall 11, it being understood that the material of the end wall will be of such character as to provide a slight yielding action which will permit of passage of the edge of the opening 20 to position in the channel 23 between the beads 22.

Disposed centrally of the removable wall 12, there is a relatively small light emitting opening 24 which is preferably circular in form.

Means is provided to concentrate the light emitted from the housing into beam form, as illustrated in Figure 1 of the drawing, and as illustrated in Figures 2 and 3 of the drawing this means consists of a body portion 26 having an inwardly turned flange 27 on one end thereof.

The inwardly turned flange is of such width that when it is turned inwardly as above described, its inner edge defines an opening 28 of substantially the same diameter as that of the light emitting opening 24 as best illustrated in Figure 2 of the drawing.

The light concentrating means in this form of the invention is permanently secured to the inner face of the removable end wall 12 by placing the outer face of the flange 27 in contact therewith and securing it in such position by a suitable adhesive, stapling, or the like.

In that form of the invention illustrated in 40 Figure 4 of the drawing, the light concentrating means consists of a tubular member 30 which is of an external diameter to have a friction fit within the opening 31 of the removable end wall 32 of the housing 33. This tubular member 30, when in operative position, has a 45 portion 34 which projects slightly into the housing 33 and a relatively longer portion 35 which projects beyond the outer face of the end wall 32.

It will be understood that in both forms of the invention, the light concentrating means will have the opaque and the fire resisting qualities or characteristics.

From the foregoing it will be apparent that the present invention provides a new and novel

lamp shade which may be readily attached to the conventional electric socket and that when in position it shields the light source and casts a concentrated beam which in itself is invisible except in the form of an illuminated spot upon the floor, such as illustrated at A in Figure 1 of the drawing.

The combined plug and socket fixture provides means by which the device may be attached to the conventional electric socket with the socket disposed inwardly of the housing to receive a lamp 37, as illustrated in Figure 2.

While the invention has been herein disclosed in its preferred form, it is to be understood that it is capable of embodiment in such other forms as rightfully fall within the scope of the appended claim.

Having thus described the invention, what I claim as new and desire to secure by Letters Patent, is:

A shade of the type described comprising in combination, a cylindrical housing, an opaque lining therefor, an end wall having a lamp socket receiving opening therein fixedly secured to one end of the cylindrical housing, an opaque lining for said fixed end wall, a removable end wall having a light emitting opening therein for closing the opposite end of the housing, an opaque lining for said removable end wall, and means carried by said removable end wall for concentrating the light emitted from the light emitting opening thereof into beam form, said means comprising a cylindrical member having a flanged end defining an opening of a diameter equal to that of the opening in the removable end wall, said member projecting inwardly from and being secured to the inner face of the removable end wall with its opening in registration with the opening therein.

BENJAMIN HENDON.
